Primary Examiner—Ian Simmons*Assistant Examiner*—Charles Hanson(74) *Attorney, Agent, or Firm*—Foley & Lardner LLP(57) **CLAIM**

We claim the ornamental design for a double walled metallic bowl, as shown and described.

DESCRIPTION

FIG. 1 is a top perspective view of a double walled metallic bowl showing my new design;

FIG. 2 is a front elevational view thereof, the rear elevational view, the left end elevational view and the right end elevational view being the same as the front elevational view shown;

FIG. 3 is a top plan view thereof;

FIG. 4 is bottom plan view thereof; and,

FIG. 5 is a sectional view thereof taken along line 5—5 of FIG. 3.

The ornamental design which is claimed is shown in solid lines in the drawings. The broken lines shown in FIGS. 4 and 5 define the bounds of the claimed design and form no part thereof.
